CLAIM

The ornamental design for a head for BBQ and kitchen tongs, as shown and described.

DESCRIPTION

FIG. 1 is an elevational right-side view of a head for BBQ and kitchen tongs, in accordance with the present invention; FIG. 2 is an elevational front-side view of the device of FIG. 1;

FIG. 3 is an elevational left-side view of the device of FIG. 1;

FIG. 4 is an elevational back-side view of the device of FIG. 1

FIG. 5 is an elevational grasping-side-looking view of the device of FIG. 1;

FIG. 6 is an elevational handle-looking view of the device of FIG. 1; and,

FIG. 7 is a perspective view of the device of FIG. 1. The broken lines showing the tong handle depict environment only and form no part of the claimed design.
